UNITED STATES PATENT OFFICE.

ROY D. TYLER, OF ST. PAUL, MINNESOTA, ASSIGNOR TO G. H. TENNANT COMPANY, OF MINNEAPOLIS, MINNESOTA, A CORPORATION.

BOTTLE CRATE.

Application filed August 9, 1926. Serial No. 128,098.

My invention relates to bottle crates wherein it is desired to provide a crate particularly adapted for milk bottles so that the bottles may be held in the crate in the creamery when they are being washed or as they are filled and so that the bottles may be handled readily without danger of breaking and more particularly to provide a crate of a long wearing nature having features 10 most desirable in an article of this nature.

A feature of my invention resides in the edge or runner members which are made of metal of a channel shape, being formed so as to dove-tail along the bottom of the side walls to provide a shoe or protection to the 15 lower edge of the crate and which are provided with end tongues adapted to extend and engage with the corner reinforcing strips so that the tongues are locked by the 20 corner members on the ends in addition to the dove-tail attachment of the same. These reinforcing strips along the bottom as of the side wall of the crate also provide a support and reinforcement for the cross rods 25 which extend through the crate walls near the bottom edge thereof.

It is also a feature of my invention to provide wooden spacing blocks which are held by cross rods in a manner so as to 30 support the jar or weight that comes against the same by the rods which provide the necessary resiliency so as to protect the bottles held in the crate. The center blocks extend below the other blocks and are 35 adapted to be supported by longitudinal reinforcing rods and supports with spacer means extending between these blocks, which spacers are looped over the rod extending through the blocks and adapted to be engaged by transversely extending rods 40 which form the bottom against which the bottles rest when in place in my crate. The wooden spacing blocks help to absorb the jar of the bottle centrally of the crate and the resilient wire bottoms permit the bottles 45 to be sufficiently resiliently held so as to provide a crate wherein the bottles are so held as to be protected against being broken.

My invention includes a corner reinforcing member having portions extending down over the bottom corner and up to provide inner corner engaging tongues which are adapted to be secured to the inner corner member and firmly riveted together, thereby 50 providing a reinforced corner and at the

same time forming means for holding the tongues of the channel members which extend along the bottom of the side walls of the crate. These crates are subject to considerable wear and tear as they are pushed 60 around in the creamery and it is necessary that they be made sufficiently strong to withstand this usage and to be sufficiently rigid to protect the bottles held therein. The corner members are formed with projecting 65 lugs so that the crates may be piled one upon the other, these lugs forming projections so as to engage with the bottom of the superimposed crate and thus hold the crates in line one upon the other. 70

The sides of my crate are preferably made of a series of slats which are connected together and which are held in place by the supporting and reinforcing rods extending longitudinally and transversely, these rods 75 forming the bottom for the compartments for the individual bottles and the supporting means for the spacing blocks, while at the same time reinforcing the sides of the crate. The corner members reinforce the connecting ends of the side walls and at the same time assist in holding them together. 80

These features, together with other details of construction and particular objects of my invention will be more fully and clearly 85 set forth in the specification and claims.

In the drawings forming part of this specification:

Figure 1 is a plan view of my crate.

Figure 2 is a longitudinal section on the 90 line 2-2 of Figure 1.

Figure 3 is a sectional detail of one of the corners of my crate in elevation.

Figure 4 is a section on the line 4-4 of Figure 3.

Figure 5 is a perspective of a corner of 95 my crate, a portion of which is broken away and illustrated in cross section.

Figure 6 is a perspective of a portion of my crate.

Figure 7 is a section of a portion of my 100 crate.

Figure 8 is a similar section to Figure 7, showing a slightly different construction in the drawing.

My milk bottle crate A is designed of a simple construction having side walls 10 and end walls 11 which are made up of a series of slat members 12 so as to provide the side walls 10 and the ends 11. 105

The construction of the walls in the crate A by the slats 12 permits a more desirable construction than if the sides were made up of single board members and facilitate the easy assembly of the crates from standard parts previously prepared and made up. The top slat 12 of the crate A is adapted to be spaced from the lower slats in a manner to form an opening such as 13 in the walls 10 and 11 which permit the crate to be easily engaged so as to lift or carry the same. This also provides a space to permit the air circulation through the crate, particularly when the crates are set one upon the other as is illustrated by a portion of the crate A in dotted outline set up in the crate illustrated in Figure 2.

In making up the crate A of the slats 12, the lowermost slats are provided with a 20 channel-shaped reinforcing member 15 made of metal or other suitable material and having the side walls 16 dove-tailed into the lower edge 17 of the slat to attach the reinforcing member or shoe 15 to the lower edge 25 of the slats forming the walls 10 and 11. This provides a reinforced lower edge about the entire crate A.

The channel-shaped reinforcing members 15 are provided with tongues 18 on the ends of 30 the same which are formed by cutting away the bottom portion of the channel members 15 leaving a very thin web-like portion 19 connecting the tongues 18. Before cutting away the bottom portion of the ends to form the 35 tongues 18 of the channels 15, a saw-cut slot 20 is formed in the lower edge of the channel members 15 adjacent the ends. This forms a gauge to determine the length of the tongues 18 and also forms a stop shoulder 40 which will be hereinafter described.

Each of the corners of my crate A is provided with outer members B which are angular in shape and are formed of suitable metal having the edges 22 turned inward into 45 a saw-cut groove formed along in the slats 12 and to provide a smooth connection of the corner member with the slats down along each corner of the crate A.

The corner members B are formed on their 50 lower end with an inwardly projecting portion 23 which projects across the corner of the bottom of the crate and is miter-cut at 24 so as to bifurcate the ends of the channel and permit the folding of the ends 25 on the 55 inner side of the corner. The corners of the crate A are provided with an inner corner angle member C which extends down to the portion 23 and which is adapted to be engaged on its lower end by the ends 25 60 which are turned up against the lower end of the corner member C. By means of suitable rivets 26 the outer corner member B with its ends 25 are clamped firmly through 65 in the corners to attach the bifurcated ends with the portions 25 firmly against the inner

angle member C. This provides a very rigid, firm construction at the corners of the crate or the crate A, reinforcing the corners in a manner so as to provide a very strong construction. The rivets or bolts 26 extend 70 through the lower slats 12 and firmly lock the parts together at the corner.

In attaching the inner corner member C with the outer corner member B at the bottom edge of the crate, when the end flaps 25 75 are folded in over the bottom of the corner of the crate, these flaps are of the same width as the cut-away portion 19 of the ends of the reinforcing members 15, so that these flaps 25 fold over and are held closely against 80 the portion 19 of the channels 15, locking the tongues firmly at the corners of the crate and providing a construction for the crate with the lower edge of the corner member B, such as the portion 23, flush with the lower 85 edge of the channel member 15. This provides a crate with a smooth bottom, yet having strong reinforced corners which will stand considerable wear and tear in the use 90 of the crate.

The channel reinforcing edges 15 may be formed with one side wall such as 16' longer than the other, as illustrated in Figure 8, so that this long side 16' may be positioned on the outside of the crate to provide an 95 outer wide reinforcing strip about the entire crate.

The inner corner members C are formed with upper projecting lugs 28 which are adapted to fit into the corners of the superimposed crate A, a portion of which is illustrated in dotted outline in Figure 2, so as to hold the crate so that they may be stacked one upon the other.

It is important in my invention that the 105 outer angle members B at the corners are provided with the integral flaps 25 which fold over the end tongues 18 of the reinforcing channels 15.

My crate A is provided with a series of 110 spacing blocks such as 30 which are made of wood or other suitable nonmetallic material to provide spacers to divide the crate for the bottles and to provide bottle compartments. I have also provided spacing 115 blocks 31 which are centrally disposed between the blocks 30 and which are of a longer nature, the purpose of which will be herein-after described.

The blocks 30 have longitudinal rods 32 120 extending through the same which extend through the ends 11 of the crate and are riveted thereto so as to support the blocks longitudinally of the crate and to form partitions for the bottle compartments. Additional supporting rods 33 extend through the blocks 30 and 31 transversely to the rods 32 125 so that by means of the rods 32 and 33 bottle compartments E are formed in the crate A. In my drawings I have illustrated 130

the crate A with a series of twelve compartments for individual bottles.

Below the compartments E I have provided a pair of parallel rods 35 which extend longitudinally of the crate A and each pair of which are positioned in line to provide bottom portions for the respective compartments E, so that there are three pairs of rods 35 extending longitudinally of the crate A and which are riveted in the end walls 11 near the top of the reinforcing channel 15. Thus the reinforcing channel 15 also reinforces the lower slats on the ends 15 so that the attachment of the rods 35, which must be close to the bottom, will not split the lower edge of the slat and which will assist in carrying the load that the rods 35 must carry when the crate A is full of bottles.

The long center blocks 31 perform a very important function in my crate by extending down low enough in the crate to permit the transverse rod 36 to pass through the same. This rod 36 is adapted to carry the channel supporting spacers 37 which loop over the rod 36 and through which the rods 35 extend. These spacers 37 are placed between the sides 10 and the center blocks 31 on the outer sides of the crate A, while the center spacing channel 37 is placed between the two blocks 31. This structure provides a central supporting means for the rods 35 which is adapted to direct the load of the rods 35 to the longitudinal rods 32 and the transverse rods 33 through the blocks 31 through which the rods 32 and 33 will pass. By this crate reinforcing means which extends transversely and longitudinally of the crate with these spacing blocks 30 and 31, I provide a crate structure of a very strong and durable nature, yet permitting sufficient flexibility for the compartments E so that the bottom rods 35 will give sufficiently to prevent the breaking of the bottles under ordinary strain and to permit sufficient resiliency so that in handling the bottles in the crate A they will not ordinarily be broken. The nonmetallic spacing blocks 30 and 31 naturally assist in this as they hold the bottles so spaced apart that they will not strike with any degree of force against the sides formed by the rods 32 and 33 and thus holding the bottles practically against the wooden blocks 30 and 31 and the wooden sides 10 and 11 and spacing them apart in the compartments E to prevent breaking of the same. The bottles may be turned upside down for washing and the crates are so constructed as to stand the heat from the steam in the washing of the bottles, together with permitting the crates to slide along gravity carriers very freely to the reinforced and smooth metal bottom which is formed about the entire crate, or to permit the crate to be slid along easily on the floor without any

danger of it being split or broken under ordinary use.

In this manner I provide a crate longitudinally and transversely reinforced by the rods, together with the blocks and spacing members 37; while the corners are strengthened by the inner angle member C and the outer angle member B with the overlapping corner flaps 25 which are firmly riveted by the rivets 26 and the lower edges fully protected by the channel members 15 which are locked with the end tongues 18 beneath the lower edge of the corner members A and firmly secured to the inner and outer corner members. This provides a simple practical structure for a milk bottle crate which will be very durable and of such a nature as to provide a long wearing bottle carrier. Dairies and creameries have found that my crate is most desirable owing to the simple and inexpensive structure, yet having very strong reinforcing means at the bottom corners and along the lower edge to fully protect the crate.

In accordance with the patent statutes I have described the principles of operation of my crate and while I have endeavored to illustrate the best embodiment thereof in the drawings, the structure shown is only suggestive of a means of carrying out my invention and I desire to have it understood that the same may be carried out by other means and applied to uses other than those above set forth within the scope of the following claims:

I claim:

1. A bottle crate including, sides made of a series of slat members, inner and outer corner reinforcing members adapted to be clamped together to hold said slat members in place, reinforcing channel members dovetailed onto the lower edge of said side walls, cut out portions formed on said reinforcing members, and means formed on said outer reinforcing corner members adapted to overlap said cut out portions to rigidly secure the ends of said reinforcing members in the corners of said crate.

2. A crate having side and end members, inner angle members, outer angle members, the outer angle members having bifurcated ends to provide inwardly folding flaps adapted to be secured to the inner angle members, reinforcing channel members for the lower edge of the side and end members, cut out portions in said reinforcing channel members defining shoulders and said bifurcated ends being locked in position by said shoulders.

3. A crate having side and end members, inner angle members, outer angle members, the lower ends of said outer angle members having integral flaps thereon adapted to be secured to the inner angle members, a U-

shaped reinforcing member for the lower edge of the side and end members, cut out portions in said U-shaped reinforcing members at the ends thereof with which said flaps are adapted to engage.

4. A crate having side and end members, inner angle members, outer angle members, integral flaps upon said outer angle members adapted to be secured to the inner angle members, reinforcing channel members for the lower edge of the side and end members having slots cut transversely therein, spaced from the ends thereof and cut out portions extending from said slots to the ends of said reinforcing channel members with which said flaps are adapted to engage.

5. A crate having side and end members, angle corner members, reinforcing channel members for the lower edges of said side and end members, cut away portions in said reinforcing channel members at the ends

thereof, and flap portions extending from said angle corner members adapted to fold over the cut away portions of said channel members and riveted to said side and end members to form a corner joint wherein said flaps provide a reinforcing wearing edge at the corners flush with the bottom of said channels.

6. A crate including, side and end portions, reinforcing channels for the lower edges of said side and end portions, having a bottom wearing edge, the wearing edge of the end portions of said channels being cut away, angle corner members for said side and end members having flaps for extending over the cut away portion of said channel members to provide a wearing edge at the corners of said crate which extends approximately in the same plane with the wearing edge of said channels.

ROY D. TYLER.
